UNITED STATES PATENT OFFICE.

CHARLES F. LEMBKE, OF VALPARAISO, INDIANA.

INTERNAL-COMBUSTION ENGINE.

1,106,720.

Specification of Letters Patent. Patented Aug. 11, 1914.

Application filed January 18, 1912. Serial No. 671,067.

To all whom it may concern:

Be it known that I, CHARLES F. LEMBKE, a citizen of the United States, residing at Valparaiso, in the county of Porter and State of Indiana, have invented certain new and useful Improvements in Internal-Combustion Engines, of which the following is a specification.

My invention relates to improvements in internal combustion engines, in which an improved rotating sleeve valve is provided in conjunction with improved accessory actuating mechanism and lubricating mechanism coacting therewith.

The objects of my invention, broadly speaking, are to increase the efficiency of an internal combustion engine; to simplify the construction of the mechanism required for such an engine; to economize on the number of parts required and combine them advantageously; to provide novel and simple means of lubrication, complete water jacketing, and a novel rotating sleeve valve having suitable ports, in combination with suitable inlet and exhaust passages, valve casing, cylinder, piston, crank shaft, etc.

My invention has also for its object the constant and synchronous lubrication of the rotating sleeve valve, cylinder, valve gears, etc., by means of an improved combination of mechanism; and to combine with the rotating sleeve valve improved coacting mechanism embodying novel features of construction of the various devices described and particularly of the valve mechanism.

The invention will be more fully explained hereinafter with reference to the accompanying drawings, forming a part of this specification, and in which—

Figure 1 is a side view of a four-cylinder engine embodying my invention, shown partly in section and partly in elevation. Fig. 2 is a transverse vertical section through one cylinder, on a section line approximately coinciding with the axes of the exhaust passages and indicated by line 2—2 on Fig. 3, and line 2—2 of Fig. 1. Fig. 3 is a horizontal sectional view of the exhaust and inlet passages and water jacket. Fig. 4 is a detail vertical sectional view of one cylinder, showing the disposition of inlet and exhaust as indicated by line 4—4 on Fig. 3. Fig. 5 is a top plan view of the rotating sleeve valve. Fig. 6 is a vertical section of the rotating sleeve valve. Fig. 7 is a side elevation of the rotating sleeve valve.

Like letters refer to like parts throughout the several views.

While the engine illustrated is of the four-cylinder, four-cycle type, it is obvious that my invention is not confined in its possible application to such engines alone.

In the drawings V indicates the cylinder, W the piston, X the connecting rod, Y the crank shaft, and K the fly wheel mounted on the crank shaft. The rotating sleeve valve A is rotatably supported in the valve casing B, which preferably is comprised of outer and inner castings provided with an annular bur U to secure a water tight joint. The valve casing B is positioned concentrically to the cylinder and surrounded by the water jacket H.

In order to actuate the rotating sleeve valve A, it is provided with the valve worm gear D, rigidly secured thereto, and rotated by the worm gear O, mounted on the shaft N, which receives its motion from the stud gear G, which engages with the stud gear G¹, mounted on the crank shaft y. The stud gears are of equal diameter. The worm gears O and D bear the proportion of 1 to 4. My preferred form of rotating sleeve valve A and valve casing B is cylindrical in its lower portion and tapering in frusto-conical form in its upper portion, as illustrated in the drawings. The rotating sleeve valve A, except at its base, is completely incased within the valve casing B. Ports C and C, which serve alternately as exhaust and inlet ports, are provided in the rotating sleeve valve and positioned diametrically opposite to each other, as illustrated in Fig. 5.

To prevent the escape of gas between the rotating sleeve valve and valve casing, a spring ring R is provided and positioned a short distance below the valve ports, between the inner surface of the rotating valve and the adjacent surface of the valve casing, in a groove in the valve casing. To permit of lubrication of the spring ring R, orifices R¹ are provided in the rotating valve and positioned so as to admit oil to and around the spring ring R.

Constant lubrication of the rotating sleeve valve is maintained by means of oil grooves F arranged spirally about the valve from its base to its annular uppermost portion on both its external and internal surfaces. The annular uppermost portion of the rotating sleeve valve is formed so as to leave a small

annular oil channel F^1 between the upper end of the valve and the valve casing.

To provide for a continuous supply of oil to the base of the rotating sleeve valve A, 5 an oil dipper X^2 is provided on the bearing X^1 of the connecting rod X, to splash oil from a crescent-shaped oil pan L provided for that purpose and positioned horizontally relative to the crank shaft, to the base of 10 the rotating sleeve valve A, over the valve worm gear D and worm gear O, and into the cylinder V, as illustrated in Figs. 1 and 2. Suitable partitions divide the oil pan into as many compartments as there are cylinders 15 to the engine, but permit oil to flow from one compartment to another. For the purpose of conveying oil to the oil pan L, troughs M are provided at each side of the crank case, as illustrated in Fig. 1.

20 For the purpose of constantly supplying oil to the oil troughs M and thence to the oil pan L, from whence oil is splashed to the rotating valve, and for the further purpose of synchronously lubricating the crank 25 shaft journal Y^1 which is provided with an oil orifice Y^2 and the journal N^1 , which is provided with an oil orifice N^2 , to lubricate the upper shaft N, the fly wheel K, mounted on the crank shaft Y, is provided with fly 30 wheel oil-splashes K^1 which splash oil from the oil well P, contained in and formed by the inclined base of the crankcase Q, to the journals Y^1 and N^1 and to the troughs M. P^1 indicates a suitable oil pipe to the crank 35 case Q.

To conduct the explosive fluid into the cylinder, oppositely-disposed inlet passages I are provided, leading through the valve casing B to corresponding ports I^1 in the 40 cylinder. To allow the burned gases to escape from the cylinder following the explosion, oppositely-disposed exhaust passages E leading through the valve casing from corresponding exhaust ports E^1 are provided in 45 the cylinder. The exhaust passages and inlet passages are arranged in sets as illustrated in Fig. 3, and lead to oppositely-disposed exhaust and inlet ports.

To maintain an even temperature in the 50 engine, a water jacket H is provided, surrounding the valve casing and encircling the cylinder, cylinder head, inlet passages and exhaust passages, as illustrated in Figs. 1 and 2. S indicates the water return pipe. 55 T and U are burs to secure water-tight joints.

In operation the crank shaft rotates the stud gear G^1 which engages with and rotates the stud gear G, thus rotating the shaft N 60 and the worm gear O mounted on the shaft N. The worm gear O engages with and rotates the valve worm gear D, thus producing rotation of the rotating sleeve valve A to which it is rigidly secured. Obviously, 65 the shaft N may be extended and provided

with as many valve-actuating gears as there are rotating valves, depending on the number of cylinders in the engine. Oil is conveyed to oil pan L through the troughs M, from the oil well P. Excess of oil overflows 70 from one compartment to another in the oil pan, the partitions being of gradually decreasing height, and from the last compartment overflows into the oil well P at its shallow end. 75

Oil splashes K^1 splash oil to the journals Y^1 and N^1 and at the same time to the troughs M, thus supplying oil to the oil pan L.

With each return stroke of the piston W 80 oil from the oil pan L is splashed by the oil dipper X^2 on the connecting rod bearing X^1 of the connecting rod X to the cylinder V, over the valve gear D and worm gear O and about the base of the rotating sleeve 85 valve A, whence it is conveyed upward over the outer and inner surfaces of the rotating valve through the spirally-arranged oil grooves F and into the oil orifices R^1 to the spring ring R. 90

The worm gear O, engaging with the valve worm gear D, causes the rotating sleeve valve A to rotate at quarter speed. In the course of the rotation of the rotating sleeve valve, its oppositely-disposed ports C engage over the opposite inlet passages I, leading to the cylinder inlet ports I^1 , to admit the explosive fuel into the cylinder with the downward stroke of the piston. The inlet passages are then covered again as the valve rotates. When the explosion occurs the pressure of the exploded gases against the rotating sleeve valve A through the cylinder ports I^1 and E^1 lifts the rotating sleeve valve slightly within the valve casing and makes 105 gas-tight joints at the exhaust and inlet ports. 110

As the rotating sleeve valve nears the completion of a half rotation, with the return stroke of the piston following the explosion, the burned gases are expelled through the cylinder exhaust ports E^1 , over which the opposite ports C in the rotating sleeve valve engage, coinciding with the exhaust passages E. The exhaust ports E^1 are then covered 115 again by the rotating sleeve valve just before the rotation of the valve is completed and as the piston nears the end of the return stroke following the explosion.

While the specific mechanism set forth herein is the preferred embodiment of my invention, it is capable of various modifications in constructional details without departing from the essential features of my invention, and 120

I therefore claim:

1. The combination of a ported, rotating sleeve valve having spiral oil grooves extending from end to end, oil orifices peripherally disposed in the valve, a hollow 130

5 sleeve-shaped valve casing rotatably supporting and enveloping the valve except at its base, a surrounding water jacket adjacent to the walls of the valve casing, a
 10 spring ring positioned between the valve and valve casing coincidently with the aforesaid oil orifices, an annular oil channel at the end of the valve into which the spiral oil grooves open, and oil-splashing mechanism,
 15 substantially as set forth.

2. In an internal combustion engine, the combination of an oppositely-ported cylinder, a piston therein, a crank shaft operatively connected with the piston, a concentrically-positioned sleeve valve casing having an outer and inner shell, a sleeve valve spirally grooved from base to its annular uppermost portion, rotatably seated between the outer and inner shells of the aforesaid 20 casing, inlet and exhaust passages coincidently disposed with the cylinder ports, a waterjacket surrounding the cylinder, inlet and exhaust passages and valve casing and separating the valve casing and cylinder, 25 and means for splashing oil to the valve mechanism, cylinder, gearing, etc., substantially as described.

3. The combination of a frusto-conical valve casing formed of an outer and inner shell, a rotatable sleeve valve seated between the aforesaid shells of the valve casing and having spiral oil grooves extending over the incased portion of the valve to its annular uppermost portion exteriorly and interiorly, 35 and an oil channel formed by the walls of the valve casing positioned over the apex of the valve with which the spiral oil grooves connect, means for supplying oil to the spiral oil grooves at the base of the valve, 40 and a water jacket encircling the valve casing adjacent to both its outer and inner shell, positioned substantially as illustrated

and described, whereby lubrication is improved.

4. The combination of a ported, rotating 45 sleeve valve having spiral oil grooves extending from end to end, oil orifices peripherally disposed in the valve, a hollow sleeve-shaped valve casing rotatably supporting and enveloping the valve except at its base, 50 a surrounding water jacket forming a complete envelop for the valve casing, a spring ring located in the outer wall of that portion of the water jacket adjacent to the cylinder coincidently with the aforesaid oil 55 orifices, an annular oil channel at the end of the valve into which the spiral oil grooves open, and oil-splashing mechanism.

5. In an internal combustion engine, the combination of an oppositely ported cylinder, 60 a piston therein, a crank shaft operatively connected with the piston, a concentrically positioned double-walled sleeve valve casing frusto-conical in its upper portion, a rotatable sleeve valve frusto-conical 65 in its upper portion having complete spiral oil grooving disposed over its exterior and interior surfaces from base to its annular uppermost portion opposite inlet and exhaust passages coincidently disposed with the cylinder ports, a water jacket encircling the valve casing adjacent to both its outer and inner shells, means for splashing oil to the base of the spirally grooved valve, cylinder and gearing, located and operatively 70 connected substantially as and for the purposes set forth in this specification.

In testimony whereof I affix my signature in presence of two witnesses.

CHARLES F. LEMBKE.
